UNITED STATES PATENT OFFICE

HAROLD A. BURT, OF ST. ALBANS, NEW YORK, ASSIGNOR TO MERGENTHALER LINOTYPE COMPANY, A CORPORATION OF NEW YORK

TYPOGRAPHICAL COMPOSING AND DISTRIBUTING MACHINE

Application filed October 1, 1930. Serial No. 485,592.

This invention relates to typographical machines, such as linotype machines of the general organization represented in Letters Patent No. 436,532 to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to machines equipped with a plurality of magazines containing matrices of different font or face, and any selected one of which may be brought into action at will.

In one class of such machines, the magazines are arranged in constant operative relation to a corresponding plurality of distributors (which may thus distribute the matrices into all of them simultaneously) and are movably arranged so that any selected one may be brought into operative relation to the assembling devices, the arrangement being such that the movement of the magazines may take place without disturbing their relation to the respective distributors. Such a machine, for example, is illustrated in the Kennedy Patents Nos. 1,386,786 and 1,705,977, wherein the magazines are carried by swinging base frames mounted to turn about separate and independent axes located at or near their upper ends.

When the magazines are thus arranged to turn about separate and independent axes, one stands further from the assembling devices than the other, when in operative position, and in providing for the proper actuation of the escapements of the magazine in use, it is necessary to take such difference of location of the magazines (even though small) into account. Heretofore, this difference has been compensated for by making the "push rods" or actuating slides for the escapements of the respective magazines of different relative lengths, that expedient being possible because the escapements are ordi-

narily mounted independently of the magazines, as in the Rogers Patent No. 1,109,872. Such an expedient, however, is open to the objection of requiring distinct sets of escapement push rods or slides, entailing so much extra expense in manufacture, and, moreover, in cases where the escapements are attached directly to the magazines, as herein proposed, it forbids the ready interchange of the magazines, since obviously magazines with the longer escapement push rods cannot occupy the same position as those with the shorter push rods or vice versa.

These and other objections of the prior art are obviated by the present invention, which contemplates an improved mounting of the escapement actuating devices, whereby their effective range of action may be varied to suit the particular magazine in operative position at the time. More specifically, this is accomplished by providing means, preferably under the automatic control of the swinging magazines, for setting the escapement actuating devices in different operative positions according to the magazine selected. In the embodiment illustrated, the escapement actuating devices include a series of upright centrally pivoted levers for engaging the escapement push rods, and these levers are mounted in a supporting frame which is rocked to and fro, as the magazines are lowered and raised, respectively, in order to position the pivoted levers nearer to or farther from the magazine in operative position, the axis of the rocking frame passing through the lower ends of the pivoted levers so as not to interfere with their full pivotal movement in either position of the frame.

As the escapement actuating devices are so mounted and operated, the escapement push rods of all the magazines may be of the same length and the magazines freely interchanged in position with each other, even though the escapements be attached directly to the magazines.

In the accompanying drawings the improvements have been shown as applied to the so-called auxiliary or supplementary magazines of a linotype machine rather than to the main magazines; but, obviously, they

are equally applicable to either. They have also been shown, as above stated, in connection with magazines of the independently pivoted type but again they are not so limited in their application. In fact, the improvements would be applicable in any case, where it is desired or necessary to vary the effective range of action of the escapement actuating devices, whether for one reason or another, and it should therefore be understood that the invention is not limited to any particular mode of application. It should likewise be understood that the improvements have been shown only in preferred form and by way of example, and that many changes and alterations may be resorted to without departing from the spirit or scope of the invention.

Referring to the drawings:

20 Fig. 1 is a side elevation of a linotype machine equipped with the present improvements;

25 Fig. 2 is a similar view on an enlarged scale and partly in section, taken through the lower end of the magazines and the associated assembling mechanism; and

30 Fig. 3 is a transverse section taken on the line 3—3 of Fig. 2 and looking forwardly or in the direction of the arrows.

35 The matrices X are stored according to font in the superposed inclined magazines A, only two of which are herein shown but of which a greater number might be employed, if desired. These magazines (of short length and having conductors A¹) are supported upon separate base frames B conjointly constituting a shift frame which, as later to be described, is arranged to be swung upwardly and downwardly in the machine to locate 40 either magazine in operative position to a fixed assembler entrance or raceway O. Each magazine has attached directly thereto a series of matrix releasing escapements C, having the customary push rods or actuating slides C¹, and it may here be stated that all 45 of the magazines and their escapements (those shown as well as those to be substituted therefor) are all alike or identical in construction so that they may be freely interchanged in position with each other, that is to say, so that any one of the magazines may be placed on either the upper or lower base frame B, as circumstances may require.

50 When a selected magazine is in operative position, its escapements C are actuated by means of a series of key-controlled devices, comprising the upright levers D, the small intermediate levers E, and the vertically movable reeds F. Since the magazines are 55 of the auxiliary variety, the reeds F are not operated directly from the keyboard mechanism, but instead are operated therefrom through the medium of bails G (see the Kennedy Patent No. 1,561,244). The levers D herein shown are of the centrally pivoted

type, being provided with open notches or bearings D¹, which fit removably upon a common transverse pivot rod D² attached to the opposite end walls of a supporting frame H. As shown in Fig. 3, the frame H is slotted 70 in its rear face to receive the levers D and to maintain them in proper spaced relation. It may be noted that in normal retracted position the escapement levers D at their upper ends bank against the frame stops H¹, being held in such retracted position by springs F¹ connected to the reeds F (Fig. 1) and pulling downwardly thereon. The small intermediate levers E are of L-shape, being forked at the upper ends of their vertical 75 arms to make pivotal connection with the lower ends of the levers D, and having the outer ends of their horizontal arms fitted into notches formed in the upper ends of the reeds F. The levers E are also mounted in the supporting frame H, being pivoted thereon by means of the rod E² and spaced apart 80 in the same way as the levers D.

85 According to the above arrangement of the escapement actuating devices, the release of the matrices from the magazine will be effected by the upward movement of the reeds F, which movement will be imparted through the small L-shaped levers E to the centrally pivoted levers D, causing the latter to rock rearwardly at their upper ends and slide the escapement push rods C¹ in the same direction to effect the matrix releasing action 90 of the escapements C. On the return stroke of the reeds F, induced by the springs F¹, the pivoted levers D will be rocked forwardly 95 to their normal retracted position and allow the escapements C by a reverse movement under the influence of their actuating springs to return to their normal matrix arresting 100 and holding position.

105 After assemblage and casting, the matrices are carried upward and delivered to the distributing mechanism, which first assorts them according to font and then releases them according to character so that they may be restored to the magazine from which they started. In the present instance, the distributing mechanism is of the kind shown in the Kennedy Patent No. 1,705,977, comprising two 110 main character distributors M, arranged one above the other and each having a toothed distributor bar and a distinct set of conveying screws for propelling the matrices thereon. When released, the matrices pass to the magazines through the entrances M¹ which, as herein shown, are pivoted at their lower ends, as at M², to fixed extensions P of the distributor bracket.

115 It is important that the relation between the magazine entrances and the distributors be undisturbed during the shifting of the magazines so that the distribution of matrices may be carried on continuously in the manner required. Consequently (see Fig. 1) the base 120

frames B are mounted to turn about separate and independent axes B¹, located at the junction of the magazine entrances and their respective magazines (as in the Muehleisen Patent No. 1,221,360), being hinged at these points by means of arms or brackets B² attached to the base frames, and having pins journaled in suitable bearings on the fixed extensions P above referred to. Near its lower end, the lower base frame is provided at its opposite edges with upstanding gage pieces or spacing blocks B³ and which have resting thereon lugs B⁴, projecting outwardly from the opposite edges of the upper base frame, this arrangement, while preserving the close spaced relation of the magazines, permitting the latter to partake of a slight longitudinal movement relatively to each other, when the base frames are swung together about their independent pivotal axes B¹.

The means herein employed for swinging the magazines consists essentially of a toggle system which is adapted to raise the shift frame as it is extended and to lower it as it is collapsed. In its lowermost position, the shift frame is supported upon a pair of set screws O¹ (Fig. 1) mounted in the framework and which are adjustable to locate the upper magazine in operative relation to the assembler throat O. In its raised position, the shift frame is supported directly by the toggle system which is so designed that, when straightened out, it will locate the lower magazine in correct registration with the throat O. The toggle system, see Fig. 1, comprises two pairs of links J, J¹ intermediately connected by a transverse rod J² to which the lower members J¹ are fastened and on which the upper members J are loosely mounted. The members J¹ are pivoted at their lower ends to fixed brackets O², and the members J at their free ends are formed with open bearings or forks j wherein engage pins a which project inwardly from lugs B⁵ depending from the lower magazine base frame. The rod J² is limited in its movements in both directions and when rocked upwardly is stopped just past "dead center" so as to lock the magazines in their raised position. The movement of the rod J² is controlled by a pivoted hand lever J³, which extends forwardly within reach of the operator, the arrangement being such that, when the lever is depressed, the rod J² will be rocked forwardly to extend the toggle member and, when raised, will shift the rod rearwardly to collapse the toggles. The shift frame is thus swung upwardly and downwardly to definite positions to bring one or the other of the magazines into operation, as desired.

The foregoing parts and their mode of operation are or may be the same as heretofore and for the most part are fully disclosed in one or another of the several patents above alluded to.

Coming now to the present invention, it will be noted from the showing of Fig. 2 that the escapement push rods C¹ occupy different positions, when the two magazines are in use. Thus, when the upper magazine is in use, as shown by the full lines in Fig. 2, the push rods are located toward the rear; whereas, when the lower magazine is in use, as indicated by the dotted lines in that figure, the push rods are located toward the front. This difference of location, as before explained, is due to the fact that the matrix releasing escapements and their push rods are alike on the different magazines and to the further fact that the magazines partake of a relative longitudinal movement during the swinging of the base frames about their separate and independent axes. Such difference, however, is permitted and compensated for in the following manner.

By referring to Figs. 2 and 3, it will be observed that the frame H before mentioned is mounted to rock to and fro about an axis passing through the lower ends of the escapement levers D or through the pivotal connection of these levers with the smaller levers E, the idea being to permit the levers D to be set with their upper ends toward the rear so as to engage and actuate the escapement push rods of the upper magazine, when that magazine is in use, as shown by the full lines in Fig. 2, or with their upper ends toward the front so as to engage and actuate the escapement push rods of the lower magazine, when that magazine is in use, as indicated by the dotted lines in Fig. 2. In other words, the escapement levers D are mounted to rock about their lower ends as a fulcrum so as to be set in different operative positions according to the magazine in use, and this without affecting the throw of the levers D, when the reeds F are operated to actuate the escapements, it being evident that the pivotal movement of the levers D about their central pivot will be the same in either of their set positions due to the neutral axis about which the supporting frame H is caused to rock. The effect is to increase or diminish the range of action of the levers D, since in one case they impart motion to the forwardly located escapement push rods of the lower magazine, and in the other case to the rearwardly located push rods of the upper magazine, the extent of such motion in both cases being the same. The action is as if the actual throw of the levers D would vary with a change of magazine, such as might be produced by a shifting of the central pivot of the levers. While such shifting of the pivot is contemplated by this invention, it is preferred to accomplish the same result by the change of position of the escapement levers, as herein specifically shown and described.

In providing for its rocking motion, the frame H is equipped at its opposite ends with

trunnions H^{10} journaled in bearings K^1 of a fixed frame K mounted in the main frame of the machine. One of the trunnions H^{10} (the one at the right looking from the front of the machine) is extended beyond its bearing and has fast thereto a rearwardly extending arm H^2 , carrying at its extremity an adjusting screw H^3 arranged to be engaged by the lower base frame. The weight of the parts is so distributed that, when the magazines are swung upwardly to locate the lower one in operative position, the frame H with its contained escapement levers D will be rocked forwardly to locate the levers in their forward position, the parts being arrested in this position by means of stop lugs H^4 formed on the frame H and adapted to engage the main vertical wall K^2 of the fixed frame K . However, if desired, a spring may be employed to impart such forward rocking motion to the frame H , provided it be light enough not to interfere with the banking of the magazines upon the adjusting screws O^1 , when in their lowermost position. On the other hand, when the magazines are swung downwardly to locate the upper magazine in operative position, the arm K^5 is engaged by the lower base frame just prior to the final banking of the magazines upon the set screws O^1 , and in the act of banking will depress the arm and thereby rock the frame H rearwardly to locate the escapement levers D in their rearward position. The former condition is indicated by the dotted lines in Fig. 2, while the latter condition is shown by the full lines in that figure.

It will now be seen that the setting of the escapement levers D in either of their operative positions is controlled automatically by the raising and lowering of magazines, the selection of the upper magazine positioning the escapement levers to the rear, and the selection of the lower magazine positioning them to the front. In this way, the difference in location of the escapement push rods is fully compensated for, allowing the magazines and their escapements to be freely interchanged with one another and with their substitute magazines.

As previously stated, the invention has been shown only in preferred form and by way of example and as applied to a particular class of linotype machine, namely, the commercial Model 26, but obviously many modifications and alterations therein and in their mode of application will readily suggest themselves to those skilled in the art without departing from the scope of the invention. It should be understood therefore that the invention is not limited to any specific form or embodiment except in so far as such limitations are specified in the appended claims.

Having thus described my invention, what I claim is:

1. In a typographical composing machine, the combination of a plurality of matrix magazines, each provided with matrix releasing escapements and movably mounted so that any selected magazine may be brought into operative position, escapement actuating devices, and automatic means for increasing or diminishing the range of action of the escapement actuating devices according to the magazine selected. 70

2. In a typographical composing machine, the combination of a plurality of matrix magazines, each provided with matrix releasing escapements and movably mounted so that any selected magazine may be brought into operative position, escapement actuating devices, and automatic means for setting the escapement actuating devices in different operative positions according to the magazine selected. 85

3. In a typographical composing machine, the combination of a plurality of interchangeable matrix magazines, each provided with like matrix releasing escapements and movably mounted so that any selected magazine may be brought into operative position, escapement actuating devices, and automatic means for increasing or diminishing the range of action of the escapement actuating devices according to the magazine selected. 95

4. In a typographical composing machine, the combination of a plurality of interchangeable matrix magazines each provided with like matrix releasing escapements and movably mounted so that any selected magazine may be brought into an operative position common to all the magazines, escapement actuating devices, and automatic means for setting the escapement actuating devices in different operative positions according to the magazine brought into the common operative position. 100

5. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, and automatic means for increasing or diminishing the range of action of the escapement actuating devices according to the magazine selected. 110

6. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, and automatic means for setting the escapement actuating devices in different operative positions according to the magazine selected.

7. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, and means actuated by the swinging of the base frames for setting the escapement actuating devices in different operative positions according to the magazine selected.

8. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, said escapement actuating devices including a series of upright centrally pivoted levers arranged to engage the escapements of the selected magazine, and means actuated by the swinging of the base frames for rocking the whole series of pivoted levers about a neutral axis

to locate them in different operative positions according to the magazine selected.

9. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, said escapement actuating devices including a series of pivoted levers arranged to engage the escapements of the selected magazine, a rocking frame whereon the escapement levers are pivotally mounted, and means actuated by the swinging of the base frames for setting the rocking frame in different operative positions according to the magazine selected.

10. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, said escapement actuating devices including a series of pivoted levers arranged to engage the escapements of the selected magazine, a rocking frame whereon the escapement levers are pivotally mounted, and an arm rigidly connected to the rocking frame and arranged to be engaged by the lowermost base frame, whereby the swinging of the base frames will automatically set the rocking frame in different operative positions according to the magazine selected.

11. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends,

- means for swinging the base frames conjointly about their respective axes to bring one or another of the magazines into operative relation to the assembler entrance without disturbing their operative connection with the distributors, a series of devices for actuating the escapements of the selected magazine, said escapement actuating devices including a series of upright centrally pivoted levers arranged to engage the escapements of the selected magazine, a corresponding series of small L-shaped levers connected at one end to the lower ends of the centrally pivoted levers, and a corresponding series of vertically movable reeds connected to the opposite ends of the L-shaped levers, a rocking frame wherein the centrally pivoted levers are mounted, said frame turning on an axis passing through the lower ends of said levers, and means actuated by the swinging of the base frames for setting the rocking frame in different operative positions according to the magazine selected.
12. A combination according to claim 6, characterized by the fact that the magazines therein recited are interchangeable with each other so that any magazine may be placed on any base frame, and characterized by the further fact that the matrix releasing escapements are alike on the different magazines.
13. A combination according to claim 6, characterized by the fact that the matrix releasing escapements therein referred to include fore-and-aft slidable push rods arranged to be engaged by the escapement actuating devices or levers.
14. A combination according to claim 9, including a fixed stop arranged to limit the movement of the rocking frame in one direction.
15. A combination according to claim 9, including a fixed stop arranged to limit the movement of the rocking frame in one direction, and an arm extended from the frame and arranged for engagement with the lowermost base frame to effect and limit the movement of the rocking frame in the other direction.
16. In a typographical composing machine, the combination of a plurality of matrix magazines, each provided with matrix releasing escapements and movably mounted so that any selected magazine may be brought into operative position, escapement actuating devices, and means for increasing or diminishing the range of action of the escapement actuating devices according to the magazine selected.
17. In a typographical composing machine, the combination of a plurality of matrix magazines, each provided with matrix releasing escapements and movably mounted so that any selected magazine may be brought into an operative position common to all the magazines, escapement actuating devices, and

means for setting the escapement actuating devices in different operative positions according to the magazine brought into the common operative position.

18. In a typographical composing machine, the combination of a plurality of interchangeable matrix magazines, each provided with like matrix releasing escapements and movably mounted so that any selected magazine may be brought into operative position, escapement actuating devices, and means for increasing or diminishing the range of action of the escapement actuating devices according to the magazine selected.

19. In a typographical composing machine, the combination of a plurality of interchangeable matrix magazines each provided with like matrix releasing escapements and movably mounted so that any selected magazine may be brought into an operative position common to all the magazines, escapement actuating devices, and means for setting the escapement actuating devices in different operative positions according to the magazine brought into the common operative position.

20. In a typographical composing and distributing machine, the combination with a plurality of main character distributors and a single assembler entrance, of a plurality of matrix magazines arranged therebetween and each provided with a series of escapements, separate base frames whereon the magazines are removably disposed and mounted to turn about separate and independent axes located at their upper ends, means for swinging the base frames conjointly about their respective axes to bring one or another of the magazines into operative relation to the assembler entrance without disturbing their operative connection with the distributors, a series of devices for actuating the escapements of the selected magazine, said escapement actuating devices including a series of pivoted levers arranged to engage the escapements of the selected magazine, a rocking frame whereon the escapement levers are pivotally mounted, and means for setting the rocking frame in different operative positions according to the magazine selected.

In testimony whereof, this specification has been duly signed by:

HAROLD A. BURT.
